FIG. 3.

FIG. 4.

UNITED STATES PATENT OFFICE.

ADISON J. JOHNSON AND ROBERT L. SKINNER, OF BETHANY, MISSOURI.

WRIST-WATCH HOLDER.

1,153,111.

Specification of Letters Patent.

Patented Sept. 7, 1915.

Application filed May 1, 1915. Serial No. 25,220.

To all whom it may concern:

Be it known that we, ADISON J. JOHNSON and ROBERT L. SKINNER, citizens of the United States, residing at Bethany, in the county of Harrison, State of Missouri, have invented new and useful Improvements in Wrist-Watch Holders, of which the following is a specification.

Our invention relates to a wrist watch holder and has as its principal object the provision of a holder for watches to be used in connection with bracelets and the like which shall be strong and simple in construction and convenient to use.

A second object of our invention is to provide a holder for hunting case watches which will include an unbroken ring of metal, but which will also include means for securely holding the watch and which will be convenient to use.

A final object of our invention resides in the particular arrangement and combination of parts hereinafter described.

In the accompanying drawings:—Figure 1 is a side view of a bracelet including our improved holder, and showing a hunting case watch therein and the case open. Fig. 2 is a view of the watch and holder shown in Fig. 1 taken from the left of Fig. 1. Fig. 3 is a view of the watch and holder shown in Fig. 1 taken from the right of Fig. 1, showing the watch case open. Fig. 4 is a perspective view of the holder shown in Figs. 1, 2 and 3. Fig. 5 is a bottom view of the holder as shown in Fig. 4. Fig. 6 is a top plan view of the holder as shown in Fig. 4. Fig. 7 is a sectional view of the modified form of holder designed for use with watch cases having no hinges thereon. Fig. 8 is a sectional view of a modified form of holder similar to the one shown in Fig. 7 except that counter-sunk screws are used.

Throughout the separate views the same part is designated by the same reference character.

Referring more particularly to the drawing, 1 is a continuous ring whose cross section is so formed that the ordinary hunting watch case fits snugly therein. Such a watch case is designated at 2. At one point the ring 1 carries an integral lug or projection 4 on which is an eye 8 to which the wristlet 9 may be secured. Diametrically opposite the lug 4 is a second lug 6 having an aperture 7 therein. It will be seen that the lug 6 lies substantially in the central

plane of the ring 1. At the same point in the circumference of the ring 1 as the lug 6 is a second lug 5 which projects laterally from the ring and which has a slot or recess 7 therein parallel to the frame of the ring adapted to receive the hinge of the watch case. Formed on the lug 4 and projecting laterally therefrom on the same side of the ring as the lug 5 are two small lugs such as 10 through which we pass a pin 4' on which is pivoted a clasp member 3, the end of the member 3 opposite the pivot 4' being formed into a lug 11 which is adapted to spring past the lug 12 which is integral with the lug 4 into a recess 13 so as to securely hold the member 3 in position when the stem of the watch has been placed in the recess 14 within the lug 4. It will be seen that the lug 5 on one side of the ring and the clasp 75 on the other coöperate with the hinge and the stem of the watch respectively to hold the same securely in place. It will be seen that the clasp arrangement is such that it cannot come loose accidentally when once 80 sprung together and will permit of a hunting case watch being easily opened. However, the clasp can be readily undone when necessary by inserting a blade between the shoulder 15 on the member 3 and the shoulder 16 on the member 4.

Referring more particularly to Figs. 7 and 8, it will be understood that many watch cases are not provided with hinges and for such cases we use instead of the slotted lug 5 a block such as 17 which is so shaped as to form a pocket or socket for holding one edge of the watch case, the stem being held by the clasp arrangement comprising the members 3 and 4 as in the form shown in Figs. 1 to 6 95 inclusive. The block 17 may be held in place by screws such as 18 having protruding heads or by screws such as 18' having counter-sunk heads, the screws in either case running through the block 17 to the ring 1. 100 The ring 19 drops toward the wrist and we find it easy to pass the bracelet chain through the ring 19 of the watch case so that the watch will not drop to the ground or be lost even if it should be forcibly torn from 105 the clasp.

It will further be seen by the drawing that the improvement will provide means by which a hunting case watch may be used with a wristlet allowing the free opening of 110 the case by pressure on the stem of the watch in the ordinary way.

Having thus described our invention, we claim:—

A bracelet watch holder comprising a continuous ring shaped to fit a watch case, 5 clasping means for holding the post of the watch case including a clasp member mounted to swing in a plane at right angles to the plane of the ring, and a member diametrically opposite from said clasping means and

rigid with the ring for holding the watch in 10 place on the ring, said last mentioned member being integral with the ring and having a recess therein for receiving the hinge of the watch.

In testimony whereof we affix our signatures.

ADISON J. JOHNSON.
ROBERT L. SKINNER.
